ARC LAMP

Otto A. Kerner, Los Angeles, Calif., assignor to
Glycere M. Kerner, Los Angeles, Calif.

Application September 26, 1930, Serial No. 484,603

9 Claims. (CL. 176—55)

This invention relates to an arc lamp having a special construction adapting it for burning short carbons or carbon pencils of unusually short length. In this connection it should be understood that an ordinary arc lamp has an automatic clutch which connects with the upper carbon to pull the same away from the lower carbon to form the electric arc. On account of the position of this clutch there is considerable waste due to the fact that this type of lamp cannot completely consume the carbons, in fact the stubs from such lamps are usually about forty per cent of the length of the complete carbon when the operation of the lamp commences with it; in other words, there is a loss of about forty percent of the lengths of carbons burned with such lamps.

The general object of this invention is to produce an arc lamp of simple construction which can operate with the waste carbon stubs which have already been used in regular arc lamps, and one of the objects of the invention is to provide a simple construction for holding the carbon stubs and maintaining the electric arc, and having a clutch mechanism located and operating in such a way that it operates independently of the length of the carbons held in the lamp.

A further object of the invention is to provide a carrying mechanism for the carbons with means for limiting the consumption of the carbons, thereby preventing any possibility of the carbons burning off and incidentally burning the ends of the arms that carry the carbons.

Further objects of the invention will appear hereinafter.

The invention consists in the novel parts and combinations of parts to be described hereinafter, all of which contribute to produce an efficient arc lamp.

A preferred embodiment of the invention is described in the following specification, while the broad scope of the invention is pointed out in the appended claims.

In the drawing:

Figure 1 is a vertical section through the casing of a lamp embodying my invention, certain parts being broken away.

Figure 2 is a plan upon an enlarged scale and illustrating one of the carbon clamps and showing a short portion of the supporting arm for the carbon broken away.

Figure 3 is a side elevation with certain parts broken away and illustrating a modified construction of the means for causing the arms supporting the carbon stubs to move in unison.

Referring more particularly to the parts, 1 represents a casing of box form, provided on its forward side with two slots 2, one above the other, through which project the arms 3 and 4 that carry the carbon stubs 5. These carbon stubs 60 may be attached to the free projecting ends of the arms in any suitable manner, for example, by means of clamps 6 such as illustrated (see Figure 2). These arms 3 and 4 are supported on a suitable frame 7 within the casing 1 and are connected in such a way that they will move toward or away from each other in unison.

In the present instance, the arms 3 and 4 are mounted on pivotal supports 8 opposite to each other so as to swing in a vertical plane. Furthermore, I connect the arms in such a way that they move in unison toward or from each other. In addition to this, I provide clutch mechanism automatically controlled, which is located within the casing and which operates independently of 75 the lengths of the carbon stubs. In order to accomplish this I provide the arms 3 and 4 with short arms or extensions 9 that project toward each other, and these extensions carry links 10 respectively that are connected by the pivot pin 80 or screw 11, said screw also serving to connect the links to the upper end of a radius rod 12 which is pivotally attached at 13 near the bottom of the casing.

In order to pull the arms 3 and 4 apart to form 85 the electric arc indicated at 14, I provide a stem 15 that is connected with one of the arms. This stem is preferably suspended from the upper arm 3 at 16a by means of a link 16. The lower end of the stem 15 is guided to slide through a guide 90 opening 17 in a fixed extension 18 of the frame 7. This stem 15 is a clutch stem and operates with a clutch 19 of a common type, said clutch being in the form of a plate having a loose connection 20, at one end, to the frame extension 18, and having 95 an opening or clutch throat 21 that bites into the side of the stem 15 when the clutch plate is pulled upwardly at its free end by means of a short link 22.

This short link 22 is pivotally connected to a 100 short arm 23 pivotally mounted on a pivot bolt 24. This same pivot bolt operates to support a clutch lever 25 that is located between the two arms 3 and 4 and this lever is provided with a laterally projecting dog 26 that engages an adjusting set screw 27 mounted in the short arm 23 and projecting down beyond the same. The end of the clutch lever 25 that is disposed toward the carbons 5 is connected to a dash-pot 28 to dampen the movements of the clutch lever when 110

it is actuated by a solenoid 29 located at the back of the case. This solenoid includes a coil 30 that is in circuit with the carbons 5 through the medium of insulated conductors 31 and it has a core 32 that is connected with the rear end of the clutch lever 25. This connection preferably is effected by means of a coil spring 33 which may be connected to the lever at any one of a plurality of openings 34 arranged in a row. By connecting the spring at different openings evidently the leverage of the core 32 can be adjusted and regulated to suit special requirements in adjusting the lamp.

In order to enable the effect of the dash-pot 28 to be regulated, its upper end is formed with an extension 35 that can be attached to the adjacent end of the clutch lever 25 in any one of a plurality of openings 36. The lower end of the dash-pot is formed by the piston-rod 37 of the dash-pot piston 38 and the lower end of this rod is pivotally attached at 39 on a fixed bracket 40 mounted in the casing.

Suitable means is provided for limiting the approaching movement of the arms 3 and 4 toward each other. This is necessary to prevent the carbons from becoming completely consumed in case the lamp is not watched. If this occurred, the arc might burn away the clamps 6. In order to accomplish this I form the stem 15 in the form of a tube and I provide a long stem 41 that is pivotally attached at 42 in the upper part of the casing and hangs down through the tubular stem 15. The lower end of this inner stem 41 is threaded and receives a stop-nut 43. It will be evident that as the arms 3 and 4 approach each other, eventually the lower end of the tubular stem 15 would strike the upper face of this nut 43 and prevent further approach of the arms toward each other.

In the operation of the lamp the solenoid cooperates with the arc at 14 in the manner which is usual in electric arc lamps, that is to say, when the tips of the carbons 5 come together, the resistance becomes so reduced that the coil 30 will pull the core 32 inwardly and thereby operate the lever 25. This will pull up the clutch plate 19 and, through the medium of the stem 15, effect a separation of the carbons, thereby forming the electric arc at 14.

By reason of the equal angular movement of the arms 3 and 4 as they approach each other during the consumption of the carbons, it will be evident that they will always maintain the tips of the carbons near enough together to maintain an effective arc.

If desired, the outer side of the casing 1 of the lamp may be provided with a reflector indicated by the dotted lines 44.

In the operation of the lamp, carbon stubs of about four inches in length can be burned down to about one inch in length. In this way the lamp will operate to eliminate about three-fourths of the waste now occurring if carbon stubs are thrown away after being burned in ordinary electric arc lamps.

In Figure 3, I illustrate a modified construction for connecting two arms 45 to correspond with the arms 3 and 4 for carrying the carbon stubs. Instead of connecting these arms as indicated in Figure 1, I may provide one of the arms, for example, the upper arm, with a short arm 46 beyond the supporting pin 47 and the end of this short arm is connected by a link 48 with the arm 45 by a pin or a bolt 49 located as indicated.

With this link 48 crossing the line joining the

pivot points of the arms, it will be evident that the arms 45 can be made to approach or recede from each other in unison.

What I claim is:

1. In an arc-lamp for burning short carbon stubs, the combination of a frame, a pair of oppositely disposed pivoted arms having means for carrying the carbon stubs, means for connecting the arms to enable the same to swing in unison on their pivot supports, a stem connected with one of the arms and extending in a transverse direction with respect to the arms for moving the same apart to form the electric arc, a single clutch lever pivotally supported on the frame, a single clutch member pivotally attached to the clutch lever and actuated thereby and cooperating with the said stem to move the levers apart in forming the electric arc, a solenoid having a core and a coil connected in circuit with the carbon stubs, and a core connected with the clutch lever for actuating the said arms, said clutch enabling the arms to approach each other successively while the core maintains a substantially constant relation to the coil, and operating to separate the arms after each approach to keep the arc between the carbons. 80

2. In an arc-lamp for burning short carbon stubs, the combination of a frame, a pair of oppositely disposed arms pivotally supported on the frame to swing in a substantially vertical plane, means connecting the arms to enable the same to swing in unison toward or from each other, a stem pivotally suspended from the upper arm, and unattached to the lower arm, a single clutch member cooperating with the stem to raise the stem and separate the arms to form the electric arc, a single clutch lever pivotally mounted between the said arms and pivotally attached to the clutch member for actuating the same, and a solenoid having a core connected with the clutch lever and a coil in circuit with the carbon stubs, said clutch enabling the arms to approach each other successively while the core maintains a substantially constant relation to the coil, and operating to separate the arms after each approach to keep the arc between the carbons. 100

3. An arc-lamp constructed as described in claim 2, in which relatively fixed guiding means is provided for guiding the lower end of the stem. 110

4. An arc-lamp constructed as described in claim 2, in which the stem is of tubular form and an inner stem is provided supported at its upper end on the frame and passing down through the tubular stem, said inner stem provided with means at its lower end for limiting the downward movement of the tubular stem to prevent the carbons from being completely consumed. 120

5. In an arc-lamp for burning short carbon stubs, the combination of a frame, a pair of oppositely disposed arms pivotally supported on the frame to swing in a substantially vertical plane, means connecting the arms to enable the same to swing toward or from each other in unison, means on the ends of the arms for carrying the carbon stubs, a stem suspended from the upper arm, a clutch having an opening to cooperate with the stem to pull the same upwardly, means for connecting said clutch at one side of the stem with the said frame, a clutch lever pivotally mounted on the frame between the first-named levers, means for actuating the clutch by the clutch lever, a solenoid having a core connected with the clutch lever and having a coil in circuit with the carbon stubs, and means for lim- 130

iting the inward swinging movement of the arms to prevent complete consumption of the carbons and the burning of the ends of the first-named arms by the arc.

- 5 6. In an arc-lamp for burning short carbon stubs, the combination of a frame, a pair of arms extending in a general horizontal direction pivotally mounted on said frame to swing in a substantially vertical plane, means on the free ends 80
 10 of said arms for carrying the carbon stubs, said arms having extensions near their pivotal supports projecting toward each other, means connecting the said extensions to enable the arms to move in unison toward or from each other, a 85
 15 clutch including a clutch plate and a stem pivotally connected with one of said arms, and unattached to the other arm, means for guiding the clutch stem to move the arms apart to form the electric arc, a solenoid having a coil in circuit 90
 20 with the carbon stubs and having means for actuating the clutch plate.
7. In an arc-plate for burning short carbon stubs, the combination of a frame, a pair of arms pivotally mounted on said frame to swing in a substantially vertical plane, means on the free 100
 25 ends of said arms for carrying the carbon stubs, said arms having extensions near their pivotal supports projecting toward each other, a pair of links attached respectively to said extensions, 105
 30 a radius arm having a pivotal support on the frame and having a pin connecting the same with both of said links and cooperating with the same to enable the arms to move in unison toward or from each other, a clutch including a clutch 110
 35 plate and a stem pivotally connected with one of said arms, means for guiding the clutch stem to move the arms apart to form the electric arc, and a solenoid having a coil in circuit with the carbon stubs and having means for actuating the 115
 40 clutch plate.

8. In an arc-lamp for burning short carbon stubs, the combination of a casing, a frame within the casing, a pair of arms pivotally supported on the frame within the casing to swing in a substantially vertical plane and having their free 80
 ends extending to the exterior of the casing, means on the free ends of the arms for carrying the carbon stubs, a clutch-stem connected with one of said arms for moving the same, means connecting the arms to enable the same to swing toward or from each other in unison, a clutch to cooperate with the clutch-stem, a clutch-lever pivotally mounted on the frame, a clutch actuator having a short arm pivotally mounted on the pivotal support of the clutch lever and connected with the clutch for actuating the same, said clutch-lever having means for lifting the clutch actuating arm to raise the clutch and pull up the stem, and a solenoid having a coil connected in circuit with the carbon stubs and having a core connected with the clutch-lever. 85
 90

9. In an arc-lamp for burning short carbon stubs, the combination of a frame, a pair of oppositely disposed arms for carrying the carbon stubs and having pivotal supports on the frame, 100
 100 a link pivotally attached to each arm and connecting said arms, said link being mounted in a position to cross the line connecting the said pivotal supports for the arms, a stem connected with the arms for moving the same to separate the carbons to form the electric arc, a clutch cooperating with the said stem, a solenoid having a core and a coil in circuit with the carbons for actuating the clutch to form the said arc, said clutch cooperating with said arms to enable the 110
 110 arms to approach each other successively while the core maintains a substantially constant relation to the coil.
